UNITED STATES PATENT OFFICE.

EMILE ERICSON, OF PELHAM, AND ROGER WEISS, OF NEW YORK, N. Y., ASSIGNORS TO THE PENNSYLVANIA TEXTILE MILLS INC., OF GLEN RIDGE, PENNSYLVANIA, A CORPORATION OF PENNSYLVANIA.

DESIGN FOR A TEXTILE FABRIC.

Application filed December 22, 1922. Serial No. 4,661. Term of patent $3\frac{1}{2}$ years.

To all whom it may concern:

Be it known that we, EMILE ERICSON, a citizen of the United States, residing at Pelham, in the county of Westchester and State of New York, and ROGER WEISS, a citizen of the United States, residing at Kings County, in the city and State of New York, have invented a new, original, and ornamental Design for a Textile Fabric, of which the following is a specification, reference being had to the accompanying drawing, forming part thereof.

The figure is a plan view of a textile fabric, showing our new design.

We claim:

The ornamental design for a textile fabric, substantially as shown.

EMILE ERICSON.
ROGER WEISS.
